CONTACT-SPRING SWITCH ASSEMBLY

John I. Bellamy, Wheaton, and Richard P. Arthur,
Chicago, Ill., assignors, by mesne assignments,
to International Telephone and Telegraph
Corporation, a corporation of Maryland

Original application April 10, 1948, Serial No.
20,196. Divided and this application March
10, 1951, Serial No. 214,908

5 Claims. (Cl. 200—166)

1

This invention relates to a contact-spring switch assembly. The principal object is to provide an assembly of this type suitable for use in relays and other structures which make efficient use of the space they occupy on a switchboard.

This application is a division of our now abandoned application Serial Number 20,196, filed April 10, 1948.

Another object is to provide a switch assembly of the foregoing character capable of being used in relays mounted close together along a common support.

A further object is to provide a compact switch assembly which is rugged in structure and efficiently adapted for convenient operative association with cooperating parts in relay structures.

GENERAL DESCRIPTION

The switch assembly is herein disclosed in its association with relay structures. The structure with which it is shown in particular utilizes a bar-like magnetic member as a common supporting means and common magnetic return member for a row of relays. As disclosed, the common bar is of L-shaped cross-section to conform to the usual construction of relays for switchboard use. Its shape provides sufficient rigidity and strength to enable it to serve as the support member for a comparatively long row of relays.

One problem encountered in providing relay structure in the nature of the foregoing concerns assembling and adjusting the contact-making structures of the several relays of a row in the comparatively limited space allotted to each in a compact arrangement. This problem is aggravated by the fact that the contact-making structures of the several relays in a row quite commonly vary widely amongst themselves as to number and arrangement of contact-making parts contained therein, thus necessarily requiring a wide variety of assembly and adjustment steps for the contact-making assemblies located within the same row of relays. In the present structure, this problem has been largely sidestepped by providing structure enabling the contact-making assemblies for the respective relays to be pre-assembled and adjusted as separate units before assembly in final position in rows, and by providing structure enabling the actuating portions of the relays to be readily adjusted to conform to the assembled positions of the respective pre-adjusted assemblies of contact-making parts. The contact-making assemblies are thus permitted to be handled efficiently in lots of the respective types, both as to assembly and as to adjustment.

2

The accompanying drawings, comprising Figs. 1 to 11, show relay structure constructed according to the invention.

Figs. 1 to 3 are respectively, top, rear, and front views of a strip of relays according to the first embodiment.

Fig. 4 is a sectional view taken along line 4—4 of Fig. 1.

Fig. 4A shows a detail of the front portion of the magnet core.

Figs. 5 and 6, show, respectively, a plan view and a side view of the contact-making assembly shown in Fig. 4.

Figs. 7 and 8 are views taken respectively along lines 7—7 and 8—8 of Fig. 6, with certain parts omitted.

Figs. 9, 9A, 10, 10A, 11, and 11A show details of the structure.

DETAILED DESCRIPTION

The invention having been described generally, a detailed description of the disclosure will now be given.

A1. General structure

In the drawings, magnetic angle bar B serves as a common support, and as a common magnetic-return member, for relays mounted thereon in a row.

Referring particularly to Figs. 1 to 3, each relay includes an electromagnet C, its armature D, a switch assembly E actuatable by the electromagnet through its armature, and the portion of bar B occupied by these parts.

Angle bar B, as shown in Figs. 1, 2, and 4, has a horizontal top portion supporting the switch assemblies E and their associated armatures D, and a depending vertical rear portion supporting the electromagnets C. Bar B is supported horizontally between upright mounting members A, to which it is secured, as by bolts 2. Other similar relay strips may be supported above and below the one illustrated, to form the relay apparatus of a switchboard.

Attention is now directed to the fact that, as hereinafter appears, the relay structure is so designed that it will operate properly when installed in any position or attitude whatever, and that the references herein to directions and dispositions of the parts are, for the most part, merely relative.

Referring to any relay, the armature D is of the illustrated bell-crank form, with its fulcrum point at the upper forward edge of bar B. The downwardly extending front portion 22 lies opposite the free end of the associated electromag-

net C for attraction upon energization thereof. Effective attraction rotates the armature, whereupon rearwardly extending lifting portion 21 moves upwardly to operate the associated switch assembly E. Upon deenergization of the electromagnet, the armature is restored to its normal position by the tension of the traveling blades of assembly E.

Each electromagnet C includes a coil 5 and cylindrical magnetic core 4 extending therethrough. The rear end of each core 4 is threadedly received within an opening in the rear flange of bar B, rendering it longitudinally adjustable. A locknut 3 is provided to retain the core in a desired longitudinal position of adjustment.

Each coil 5 loosely encircles its core 4, and is provided with a square rear spoolhead 7, and a round front spoolhead 8.

Rearwardly extending winding terminals 11, for each coil 5, are located in a row along the lower edge of rear spoolhead 7, the square outline of which retains the coil against rotation. The upstanding base portion of any terminal 11 is kept out of engagement with bar B by an insulating spacing collar 6, which encircles core 4 between the bar and rear spoolhead 7.

During assembly, coil 5 is slipped over core 4, to the position shown in Fig. 4, prior to installation of the associated armature D, and is retained in position by spring clip 9 (Fig. 3) engaged within annular groove 10 (Fig. 4A) in the front portion of the core.

As shown in Fig. 4, sufficient clearance exists between spoolheads 7 and 8 and the horizontal portion of bar B, to prevent distortion of such bar by a crookedly mounted electromagnet bearing upwardly against the front edge thereof. Moreover, it enables the coil to be readily removed and replaced. Bar B has sufficient thickness and consequent rigidity, that it does not require the support of front spoolheads 8.

As shown in Figs. 1, 3, and 4, each armature D is arranged to pivot on the upper front edge of bar B, and is retained pivotally in position by member 24.

Upon energization of any of the electromagnets C, the associated armature D turns about its axis to bring its lower attracted portion 22 into contact with the domed end of core 4 which provides an adjustable front stop for the armature. Turning the core 4 in one direction advances it toward the armature, causing the armature to engage it sooner when being attracted. Turning the core in the opposite direction retracts it, causing the armature to travel further before it strikes it. The rotation of such armature D raises its actuating portion 21, whereby associated control studs 40, engaged at their base by sockets 20 thereof, are pushed upwardly to actuate associated traveling blades of the overlying switch assembly E.

Upon deenergization of the electromagnet, the downward tension of the associated traveling blades of assembly E serve to return the armature to its normal position. As shown in Figs. 3 and 4, the normal or backstop position of the armature is regulated by the setting of screw 26. Turning screw 26 in one direction stops armature D at an earlier point in its return movement. Turning the screw in the opposite direction permits a more extended return movement of the armature. Locknut 27 when tightened locks screw 26 in a desired position.

As shown in Figs. 1, 3, and 4, each of the armatures is held in its position on bar B by member 24. Member 24 is provided with arms 28 prefer-

ably so disposed, as shown in Fig. 4, that they make about equal angles with parts 21 and 22. The smooth working surfaces of such arms bear against the bent portion of armature D to prevent its upward or forward displacement. As shown in Fig. 1, lateral movement of such armature is prevented by the rounded side portions of the member 24. This method of mounting the armature insures its reliable operation when mounted in any desired attitude. Similar previously-known armature-retaining members required expensive milling and grinding, whereas applicant's member is punched and formed of sheet metal with a smooth side thereof forming a bearing surface for the retained armature.

A U-shaped residual plate 23, shown in Figs. 11 and 11A, is applied to armature D and then crimped in place to appear as shown in Figs. 3 and 4. Such an applied residual plate, when employed, lies between the core and the armature. By striking the core, it holds the armature out of contact therewith to insure that a desired amount of the operating air gap remains unclosed with the armature in its fully operated position. This unclosed portion of the operating air gap is commonly referred to as the residual air gap. Its length, determined by the thickness of plate 23, controls a release characteristic of the relay, as is commonly known.

It is contemplated that the relay armatures will be provided in lots, distinguished by specifically different residual-gap lengths assigned thereto, varying from zero to about .020 inch, for example. One lot will have no residual plate and will therefore provide no residual gap. The remaining lots will have residual plates of respective thicknesses. Each armature of a lot will carry a symbol indicative of the thickness of the residual plate 23 attached thereto. For example, the first armature to the left in Fig. 3 is marked "15" to indicate that its residual plate is fifteen thousandths of an inch, to provide a residual gap of that length between a fully-operated armature and its core 4.

45

A2. Switch assemblies

For convenience, the switch assemblies (shown at E) are illustrated as being all alike. Ordinarily, the assemblies vary from relay to relay according to the different circuit functions of the different relays. The assemblies may vary in the number of types of sets contained therein, and in the number of sets of any one type, from which it follows that they may vary in overall number of contact sets and in the height of the pileup, as will be readily understood.

Referring now to Figs. 5 to 8, the detached switch assembly E shown therein may be the one shown applied to any one of the relays illustrated in Figs. 1 to 4. Such switch assembly includes cap plate 32, base plate 33, and parts clamped between them by screws 24, which pass through openings in the cap plate and intervening parts to the base plate wherein they are threadedly received. Two opposed columns 30 and 31 of contact sets are included in the same unitary assembly E. This construction enhances rigidity and reduces the number of assembly and clamping screws required.

Referring now to Fig. 6, wherein the left-hand column 31 is respectively shown in profile to include four commonly denoted types of contact sets, the make-before-make set (fixed blade 55 and traveling blade 56, 57), the break-make set (fixed blades 58, 59 and traveling blade 59),

the break set (fixed blade 61 and traveling blade 62), and the make set (fixed blade 64 and traveling blade 63). The right-hand column may or may not include similar sets. Fig. 4 shows the control stud 40 of column 31 which moves the traveling blades of such column 31 into and out of electrical connection with the fixed blades of their respective contact sets in response to associated armature action. A similar stud is provided, but not shown, for column 30 which is actuated simultaneously with the stud of column 31 by the armature. Each of the contact blades of columns 30 or 31 has a terminal portion 65 for the attachment of circuit wires. The terminals are staggered, as shown in Fig. 5, for wiring convenience.

The traveling blades (57, 59, and 62) of the normally closed contacts in column 31 are downwardly tensioned by a preforming operation, and in normal position exert sufficient contact pressure against their respective fixed contact blades (55, 58, and 61) to insure that reliable electrical connection is established therebetween. The traveling blades (56 and 63) of the normally open contacts of such column are slightly tensioned downwardly to insure that they will return to their normally open position after operation.

The fixed blades are sufficiently rigid to withstand the pressure exerted against them by their respective traveling blades and are all of similar construction with the exception of fixed blade 55, which is upwardly offset at the front. Blade 55 is constructed in this manner to permit its associated make-before-break contact set to perform its usual functions with the actuating blade 56 thereof in an intermediate position between blades 55 and 57, which places the control level of such contact set at the same level of control as that of the break-make sets. This is important as the two sets are actuated at the same point on control stud 40 thus making the two sets interchangeable, which permits the use of a maximum number of combinations of contact sets with a minimum number of control stud types. The overall height of the two sets (make-before-break and break-make) is also the same. This is accomplished by affixing a spacing member 67 (Fig. 6) of the required thickness of the retained portion of the upper traveling blade 57 of the make-before-break set to raise its overall height to equal that of the break-make set. The use of such spacing member requires the use of one additional spacing member 66 in addition to the one normally required, as will be subsequently described, in the tongue-portion of the assembly to balance the set and keep the blades parallel. Figs. 4 and 6 show spacing plate 54 which is used between the break and make contact sets to separate their traveling blades 62 and 63 to avoid spacing their actuating ledges on the control studs too close together.

The traveling blades of the contact sets are relatively thin (approximately .0126 of an inch has been found to be satisfactory) and of a free length which is sufficient to impart the required flexibility thereto for effective cooperation with their respective fixed contacts. Such free length of the traveling blades normally positions its contacts and the corresponding ones of the respective fixed blades at a somewhat remote point from their secured rear end portions. While such flexibility is necessary for the traveling blades, it is equally necessary that the fixed blades have sufficient rigidity to withstand the

contact pressure of the traveling blades which is exerted against them.

The required rigidity of the fixed blades is provided by using blades which are of twice the thickness of the traveling blades (approximately .0253 inch) and by retaining them for the greater part of their length in the clamping pileup. Fig. 5 shows two such fixed blades 64, in clamped assembly, with only the contact bearing ends and a small adjacent portion of the blades exposed. Each of the fixed blades, in the manner of blades 64 in Fig. 7, has a semicircular cutout portion which permits the blades to be anchored at a point adjacent to the front ends and out of electrical contact with the forward clamping screw. Each of the fixed and traveling blades is provided with a dowel pin opening 68, which is used to hold the contact blades in alignment during assembly.

The fixed contact blades, as viewed from the side in Figs. 4 and 6, are generally straight and of the form of blades 64 shown in Fig. 7. An exception to the fixed blades being generally straight is the previously-mentioned fixed blade 55 which is upwardly offset at the front end. The fixed blades are arranged in overlying relationship in two columns 30 and 31 and positioned in the assembly as shown for their uppermost blades 64 in Fig. 7. The forward end portions of the fixed blades are laterally offset, as shown in Fig. 5 for blades 64, to enable such blades to cooperate with their respective traveling blades, the free lengths of which are laterally disposed with respect to the forward (tongue portion) of the clamping pileup.

Fig. 9 shows the generally T-shaped form of the traveling blades which are preformed and tensioned downwardly. The traveling blades are similar with the exception of blades 56 and 57. Blade 56 is similar to the other traveling blades but is somewhat shorter. Blade 57 has a deep head portion (Figs. 5 to 8) which carries two sets of contacts, a forward set which cooperates with the contacts of the upwardly offset fixed blade 55 and a rear set which cooperates with the contacts of the shorter intermediate traveling blade 56.

The traveling blades are interspersed with the fixed blades in the manner shown in Figs. 5 and 6. These traveling blades are arranged in overlying relationship with each other in the two columns 30 and 31, and with the exception of their retained rear end, lie outside the clamping pileup in the position as shown for their uppermost blades 63 in Fig. 8 to permit their desired freedom of travel. A spacing member 66, having the same thickness as the traveling blades, is used, as shown in Fig. 8, in the "tongue-portion" of the assembly adjacent to each traveling blade, to balance the assembly by compensating for that (free) portion of the traveling blades which lie outside the confines of the clamping arrangement. A control stud return spring 52 is provided for each column of contact sets 30 and 31 and is positioned at the top thereof, as shown in Figs. 4 and 5, to retain the control studs 40 in position and, where desired, are tensioned downwardly to assist in returning such control studs 40 to their normal position.

Twin contact points 53, as shown in Figs. 6 and 8, are affixed to each traveling blade adjacent to each edge of the T head portion thereof to engage similar cooperating contact points which are affixed to the laterally extended front portion of each of the fixed blades to ensure reliable

electrical contact upon the engagement of the respective fixed and traveling blades. The height of the contact points carried by the contact blades is preferably so related to the thickness of the insulators 45 that the desired stroke clearance exists between open contacts when the fixed contact blades are straight. This condition exists when the contact-point height is .004 less than half the thickness of the insulators, or approximately .019 inch.

Structural rigidity for the switch assembly E and particularly of the fixed blades thereof, is provided by the previously-described clamping means. This will be described more fully at this point, for it concerns an important feature of the invention. As disclosed, the switch assembly is independently assembled from the remaining apparatus and includes the two columns, 30 and 31 of Fig. 5, of contact blades arranged in sets. The upper clamping plate 32 of the assembly, as shown in Fig. 5, has a square rear portion and a narrow forwardly-extending "tongue-like" portion which extends forwardly for the greater part of the assembly length. Base plate 33 is somewhat similar in shape and is partially shown in Figs. 5 to 8.

The desired rigidity of the assembly (wherein two columns of contact sets are included within one structure) is provided by clamping one end of all the parts, including insulators 45 which are common to the two columns and which have the general configuration of plate 32, between the widened end portions of plates 32 and 33, and by including the tongue portions of the insulators 45 and the greater portion of the fixed blades within the confines of the clamping structure. By this arrangement, a forward anchoring point is provided for the fixed blades to keep such blades relatively rigid and level throughout which is particularly advantageous where a common actuating means is used for both columns of the assembly.

Figs. 10 and 10A show one of the insulators 45 which are common to the two columns 30 and 31, and which are used to insulate and align the contact blades thereof. Insulators 45 insulate the parts from each other and the rest of the structure, and additionally retain the contact blades and the spacing members 66 (Fig. 8) in proper assembled alignment. Insulators 45 have raised annular portions 46 and raised cylindrical portions 47 which are formed thereon by a semi-perforating operation, which leaves similar depressions on the underneath side thereof.

Figs. 7 and 8 show respectively the manner in which the annular portions 46 of any insulator 45 are inserted in openings 49 in the retained portions of the fixed and traveling blades to hold such blades in assembled alignment. Fig. 7 shows the manner in which the raised cylindrical portions 47 of any insulator 45 serve as inner-stop positions for fixed blades associated therewith. Such stop positions prevent the fixed blades of columns 30 and 31 from coming into contact with each other and with the forward clamping screw 34. Fig. 8 shows the manner in which the same cylindrical portions 47, of an insulator 45 used adjacently to a traveling blade, are inserted within provided openings in the spacing members 66 to hold such members 66 in alignment. The aforementioned depressed portions on the underside of insulators 45 permit a nesting of the insulators and their respective parts to retain such parts in alignment in clamped assembly.

A control stud 40 is provided for each column 30 and 31, as shown for column 31 in Fig. 4, for the simultaneous actuation of the traveling blades of the contact sets comprising such columns. Each stud is engaged at its base within the associated one of the pair of sockets 20 in the lifting portion 21 of armature D and passes through slots 41 (Figs. 7 to 9) in the traveling blades of the respective column and to the outside of the fixed blades thereof. Each stud has bracket-like ledge portions which engage the traveling blades of its respective column for their actuation when such stud is lifted in response to armature action. The upper central portion of each stud is engaged, as shown in Fig. 4, in slot 42 of return spring 52 (Figs. 5 and 7) which positions the stud, and aided by the tension of the associated traveling blades returns the stud and its armature to normal position upon deenergization of the associated electromagnet.

In the contact-blade construction herein disclosed (traveling and fixed blades being respectively of a thickness of .0126 and .0253 inch), and where the effective control stud location is about 1.75 inches from the support line and about .5 of an inch from the contact points, it has been discovered that satisfactory contact pressure (on the order of thirty-five grams per traveling blade for the disclosed twin-contact arrangement) is built up by an over-travel of the stud-engaged intermediate portion of a traveling blade (either upon operation of the relay or upon restoration thereof) on the order of .006 of an inch.

Observation of the amount of over-travel (travel after the contact points engage) is a reliable indication of the amount of contact pressure. This feature avoids the necessity in certain other types of contact blade construction, of applying a tension gauge to the traveling members.

In order to fulfill the objective previously stated, to provide relay structure capable of being mounted in rows along a common magnetic return member, where the limited space allotted to each makes the assembly and adjustment of the widely varying contact sets of the various relays extremely difficult, separate and pre-adjusted assemblies of various combinations of contact sets are provided which are readily mounted as a pre-adjusted unit along such member.

It has been determined that the four illustrated types of contact sets (make-before-break, break-make, break, and make) can be combined into over a thousand combinations, which will meet all normal switchboard requirements.

It is contemplated that the desired combinations of contact sets forming switch assemblies will be produced in lots in the manner previously described for the armatures, which will promote efficiency in the assembly and facility in the pre-adjustment thereof.

After a desired combination of contact sets (the illustrated contact sets comprising columns 30 and 31 of Figs. 5 to 8 for example) are clamped in assembly, such assembly is adjusted to certain operating standards.

A3. Pre-adjusting the switch assembly E

The steps required to pre-adjust a separate switch assembly E, such as the one illustrated in Figs. 5 to 8, will now be described.

The first step is to visually inspect the assembly to be adjusted to determine that all the parts are straight and in alignment. Any parts which are malformed or misaligned are manually straight-

ened. It is contemplated that accurate preforming of the parts will make this inspection a relatively simple one.

The second step is to secure the assembly (with the control studs in position) to a special jig whose electrical or mechanical action, preferably the latter, controllably raises and lowers the control studs of the assembly in a manner which simulates actual armature action, and which permits desired fine adjustments of the contact sets comprising the two columns of such assembly.

The third step is to adjust the contact sets of the assembly to an operated engagement position which closely approximates the fully operated one. Such an engagement position is one which requires only the further travel (.006 inch over-travel) of the intermediate stud engaged portion of the traveling blades of the sets to become fully operated. The engagement position is used here, and in the normal position adjustment, to facilitate adjustment of the contact sets of the assembly without regard to contact pressure, which is regulated by the correlating armature adjustment to be described later.

The foregoing adjustment is made by operating the jig to simultaneously raise the control studs 40 of the two columns of contact sets until the make contacts of the make and break-make contact sets of the two columns initially make engagement. An inspection will be made to determine if all such contact sets are engaging simultaneously, and any such sets that appear to be engaging prematurely or late, with respect to the majority of the others, are adjusted for conformance thereto by bending the exposed front portion of the upper fixed blades 64 or 60 thereof upwardly or downwardly as required. This adjustment, being the more critical, is made first and is used as a reference point for succeeding adjustments.

The fourth step is to adjust the normal engagement position of the contact sets of the assembly. This is accomplished by lowering the control studs a predetermined amount from the reference point, where the break contacts of the break and break-make sets should initially engage. Again a visual inspection determines if all such contacts are simultaneously engaging at this point and any that are not are adjusted to do so by bending the lower fixed blades 61 or 58 thereof upwardly or downwardly as required. It should be noted that it is satisfactory if the sets engage slightly above or below that predetermined point on the downward stud travel for such point of engagement is not critical.

The fifth step is to adjust the make-before-break contact sets. This is readily accomplished for any such set by bending the exposed front portion of the lower fixed blade 55 upwardly or downwardly as required. Bending blade 55 upwardly, with upper traveling blade 57 following, increases the gap between the contacts of the intermediate traveling blade 56 and the upper traveling blade 57. Bending blade 55 downwardly decreases the gap. The normal position of adjustment is where the contacts of the three blades, 55, 56, and 57, are in electrical connection at an intermediate point of stud travel with respect to the reference point and the point where the break contacts of the break and break-make sets initially disengage. Such intermediate position may be determined by a gauging operation with respect to the reference point.

The switch assembly E having been assembled

and preadjusted to certain operating patterns, it is ready for its final assembly along a common angle bar E, which as aforesaid serves as a common magnetic return member and support for the rows of relays mounted thereon. Figs. 4 to 6 show the two mounting screws 35 which freely pass through openings in the assembly and which are threaded into openings 36 (Fig. 1) in bar B to secure the assembly thereto.

A4. Final assembly steps

The final assembly of rows of relays along a common angle bar B comprises four steps which will be readily and efficiently performed by the assemblers in accordance with simple assembly sheets which may be provided.

STEP 1.—CORES

As shown in Figs. 1 and 2, bar B first fitted with magnetic cores 4 at the required relay locations. This is accomplished by threading the rear portions of the cores, in the manner previously described, into the rear flange of bar B until the front domed end of the cores directly underlies the front edge of bar B which approximates the final position of the cores. A locknut 3 is then threaded on each core, but not tightened as the frontstop position of the armatures is yet to be adjusted.

STEP 2.—COILS

Each of the assembled cores is fitted with an electromagnetic coil 5 of the desired characteristics, as shown in Fig. 4. As previously described, each coil 5 is slipped over its associated core 4 from the front and is retained in position by a spring clip 9 (Fig. 3) engaged within annular groove 10 (Fig. 4A) in the front portion of the core.

STEP 3.—ARMATURES

Figs. 1 and 3 show the manner in which each relay location is fitted with an armature D having the desired residual characteristic. Each armature, as aforesaid, is retained in its position on bar B by an armature retainer 24 which is secured to such bar by a screw 25.

STEP 4.—SWITCH ASSEMBLIES

Each relay location is fitted with a pre-assembled and pre-adjusted switch assembly E, which includes the contact sets adapted to meet the requirements of that particular relay. The switch assemblies are readily installed in position on bar B and are simply secured, as aforesaid, by two mounting screws 35. The switch assemblies lie flatly upon bar B with the protruding ends of clamping screws 34 thereof being received in provided clearance openings 37 in bar B. The control studs 40, one for each column of contact sets in each relay, are now inserted into the position shown in Fig. 4. The stud is inserted from the top of the assembly within slots 41 (Figs. 5 to 8) of the traveling blades of the respective column until its base engages its respective slot 20 in armature portion 21. The return spring 52 is upraised to permit such insertion. After the stud is so inserted, it is moved forwardly until its ledge portions engage their respective traveling blades, whereupon the spring 52 is returned to its normal position. The normal position of the spring 52 is where the top central portion of the stud 40 is held within slot 42 of such spring 52.

A5. Final adjustment steps

After the relays are finally assembled along the common bar B, only two simple armature adjust-

ments are necessary for each relay to regulate its armature travel for effective cooperation with the pre-setting of the contact sets of its associated switch assembly E. The first adjustment is to set the frontstop position of the armature travel and the second is to set the backstop position. As aforesaid, the frontstop (operated) position is set by the longitudinal positioning of the associated core 4 and the backstop (normal) position is set by the adjustment screw 26 carried by the associated retainer 24.

The frontstop position of the armature is adjusted to conform to the operated engagement position of the applied pre-adjusted switch assembly E. This is accomplished by inserting a 15 thickness gauge between armature portion 22 (or residual plate 23 if used) and the domed end of core 4. The armature is then operated until the previously-described operated engagement position (where the make contacts of the make and break-make sets initially engage) of the assembly obtains and the core 4 is adjusted, in the manner previously described, to form a frontstop position to stop the forward travel of the armature at this point. The thickness gauge used is of a thickness, that when removed, provides the desired amount of overtravel for the armature and the associated control studs to provide the desired contact pressure of the make contacts of the associated switch assembly E.

The backstop position of the armature is adjusted to conform to the normal (unoperated) position of the switch assembly E. This is accomplished, with backstop adjustment screw 26 loosened, by using the frontstop position of the armature as a reference point and inserting a thickness gauge between the domed end of the core 4 and the armature in the manner of the previous adjustment. The backstop adjustment screw is then tightened and locked in position by locknut 27 to stop the return travel of the armature at this point. The thickness gauge used thus regulates the armature travel to a desired amount and determines the normal (unoperated) position of the relay. Such normal position is one where the break contacts of all the contacts sets of the switch assembly are in engagement with sufficient contact pressure to insure their reliable electrical connection. The thickness gauge used is of such a thickness that it provides sufficient overtravel (.006 inch) for the armature to build up the satisfactory contact pressure for the break contacts and also provides for a slight additional armature return travel to provide a margin of safety which is desirable in setting the armature backstop position, which is not critical after a certain amount of such travel is allowed. The amount of armature travel which permits the break contacts of the contact sets to properly engage (normal relay position) is sufficient to cause the make contacts of the contact sets to properly disengage.

We claim:

1. In a contact-blade switch assembly, two opposed columns of superposed contact-making blades and structure for clamping them in a unitary assembly, said clamping structure including a single stack of similar superposed insulating laminations with the blades clamped between them in succeeding layers, each layer including a separate blade of each column, the two blades of a layer lying side-by-side out of contact with each other, each lamination having a relatively wide rear portion common to both columns and a relatively narrow forwardly extending central tongue portion, each column including super-

posed sets of blades each including a flexible travelling blade and a relatively fixed blade appearing in adjacent layers and arranged to engage and disengage each other at their forward end incidental to flexure of the travelling blade, each blade being clamped between the respective rear portions of adjacent laminations, the forward portion of each travelling blade being unclamped and extending freely alongside of the tongue portion of the laminations, a portion of each fixed blade being clamped between the respective tongue portions of adjacent laminations substantially throughout the length of such tongue portions.

2. In a contact-blade switch assembly as set forth in claim 1, each travelling-blade layer including a third member comprising a spacer blade lying between the tongue portions of the adjacent laminations and having the thickness of the travelling blades, whereby parallelism is maintained between the clamped laminations in a structure having travelling blades of a relatively simple outline.

3. In a contact-blade switch assembly, two opposed columns of superposed contact-making blades and structure for clamping them in a unitary assembly, said clamping structure including similar superposed insulating laminations with the blades clamped between them in succeeding layers, each layer including a separate blade of each stackup, the two blades of a layer lying side-by-side out of contact with each other, each lamination having a relatively wide generally rectangular rear portion succeeded by a relatively narrow forwardly extending tongue portion, each column including superposed sets of blades each including a flexible travelling blade and a relatively fixed blade appearing in adjacent layers and arranged to engage and disengage each other at their forward end incidental to flexure of the travelling blade, each blade being clamped between the respective rear portions of adjacent laminations, the forward portion of each travelling blade being unclamped and extending freely alongside of the tongue portion of the laminations, each fixed blade being clamped between the respective tongue portions of adjacent laminations substantially throughout the length of such tongue portions, each lamination having an opening through its rear portion and an opening through its tongue portion, said clamping structure further including overlying and underlying clamp plates, respective clamp members passing through the said openings out of engagement with the blades and engaging each clamp plate to clamp the said parts of the clamping structure rigidly together.

4. In a contact-blade switch assembly as set forth in claim 3, each lamination carrying a narrow raised locating member on one surface of the tongue portion and located along the longitudinal centre line thereof, the raised member of the concerned lamination serving at any layer of fixed blades to maintain the adjacent edges of the fixed blades out of contact with each other, each layer of travelling blades including a third member comprising a spacer blade lying between the tongue portions of the concerned adjacent laminations and having the thickness of the travelling blades, each said spacer blade having an opening receiving the said raised member of the concerned lamination and having a further opening registering with the said opening through the tongue portion of the lamination.

tions, whereby parallelism is maintained between the clamped laminations.

5. In a contact-blade switch assembly as set forth in claim 3, each lamination having five openings therethrough which include the two set forth in claim 3, such openings including four adjacent the respective corners of the rear portion, respective clamp members, including two of those set forth in claim 3, passing through the two rearmost openings and the foremost opening out of engagement with the blades and engaging each clamp plate to clamp the said parts of the clamping structure rigidly together, each clamp plate having openings aligned with the remaining openings through the laminations, the aligned openings adapted to receive screws for mounting the assembly on a support structure, whereby such screws aid in maintaining the parts of the clamping structure clamped firmly together when the assembly is mounted.
